METHOD OF AND APPARATUS FOR SETTING CUTTING STONES

Rutherford H. Taylor, Millburn, N. J., assignor to J. K. Smit & Sons, Inc., New York, N. Y., a corporation of New York

Application December 4, 1937, Serial No. 178,143

3 Claims. (Cl. 22—202)

This invention is directed broadly to an improved method for setting stones and to an improved construction of mould for use in the practice of my method, the invention more specifically relating to setting the cutting stones of diamond tool holders.

In the making of diamond tools as heretofore practiced, difficulty has been experienced in holding the cutting stone or diamond against displacement during the casting of the metal of the holder about the same. The diamond, too, is often burned or overheated in casting the holder. This causes disintegration of the skin of the stone and at times unites the stone for use as a cutting tool.

I purpose to overcome the difficulties above referred to and to provide a very much improved product by temporarily holding the diamond against displacement and protecting the same against burning by surrounding the diamond with an inert gas which is caused to flow past the diamond during the operation of casting the metal of the holder about the diamond.

In the accompanying drawing wherein I have illustrated one form of mould capable of use in the practice of my invention:

Fig. 1 is a sectional elevational view of the mould showing the diamond in place therein;

Fig. 2 shows the holder with the diamond set therein as it appears when removed from the mould; and

Fig. 3 is a section on the line 3—3 of Fig. 1.

Referring to the drawing in detail: 2 designates a mould, provided with mould cavity 4 which may be of any shape desired, as will be understood.

In the bottom of the mould cavity I provide an orifice 6 for the reception of the cutting stone 8 during the operation of casting the holder about the stone.

As above pointed out, one of the objects of my invention is to provide simple and efficient means for temporarily holding the stone in the mould so that during the operation of pouring the metal of the holder the stone will not be displaced and will not be burned or overheated.

As will be seen from the drawing, the orifice 6 is not of the same shape as the stone 8, so that with the stone resting in the orifice a current of inert fluid can be forced past the stone to hold the same against displacement with respect to the orifice and at the same time to surround the stone with the fluid to protect the stone against the heat of the metal during the casting of the holder.

Communicating with the orifice 6 is a suction

line 10. In addition to the suction line 10 a line 12 leads to the mould, and is in communication with a channel 14 in the mould, and a channel 16 leading therefrom to the top of the mould cavity. The line 12 leads to a supply of inert gas such as nitrogen.

In operation, a stone 8 is placed in the orifice 6, then with the mould parts in place suction is applied to the line 10, to draw inert gas into the mould cavity 4, to flush the same, the gas passing in a stream past the stone 8 to the line 10. The gas flowing past the stone will hold the same in place so that as the molten metal 18 of the holder is being poured into the mould I am assured that the stone will be surrounded by a current of inert gas to protect the stone against injury by the heat of the molten metal and to hold the stone in the orifice against displacement during the casting operation.

It will be understood of course that after the holder is removed from the mould it may be turned down or otherwise shaped to any form desired.

It will be seen from all of the foregoing that I have provided an improved method of and apparatus for setting cutting stones wherein I have provided an exceedingly simple arrangement for holding the stone against displacement and for protecting the stone during the moulding or casting operation.

It is to be understood that changes may be made in the details of construction and arrangement of parts hereinabove illustrated and described without departing from the spirit and scope of my invention.

What I claim is:—

1. In the setting of diamonds in a diamond tool holder, the method which comprises inserting a diamond of irregular shape into engagement with the wall of an opening of a different shape in a mould and flowing an inert fluid about the diamond and through the opening while pouring the metal of the setting into the mould to prevent injury to the diamond from the molten metal.

2. A mould for the setting of cutting stones in a holder, comprising in combination a mould cavity having an orifice for the reception of a cutting stone of a shape other than the shape of the orifice whereby with the stone in the orifice spaces will be provided between the sides of the stone and the walls of said orifice, and means for passing an inert gas in a continuous stream through the said spaces along the sides of the stone and through the orifice to envelop the stone in the inert gas and hold the stone against dis-

placement while pouring the metal of the holder into the mould cavity.

3. A mould for the setting of cutting stones in a holder, comprising in combination a mould cavity having an orifice in the bottom thereof for the reception of a cutting stone of irregular shape, a suction line communicating with the mould cavity through said opening, and means for supplying an inert gas to the mould cavity to

be drawn by the suction line in a continuous stream along the sides of the cutting stone and through said orifice to protect the stone against the heat of the molten metal and to hold the stone against displacement in the orifice during the pouring of the molten metal of the holder into the mould. 5
